FABRIC CUTTER

Albert Thomas Guest, Los Angeles, Calif.

Application November 29, 1948, Serial No. 62,470

2 Claims. (Cl. 30—293)

1

This invention relates generally to fabric cutters, and specifically to a cutter for trimming selvedge edges from wall paper or the like.

In paper-hanging operations, it is sometimes necessary or desirable to cut a selvedge edge or other parallel strip from the paper in order that matching of designs may be made. Frequently it is desirable to be able to cut this parallel strip from the main sheet while holding the sheet closely to a panel already on the wall.

An object of the invention is to provide a portable cutter capable of being held in the hand and used along the edge of a sheet of fabric or paper to remove a portion thereof.

Another object of the invention is to provide a cutter for wallpaper with which the narrow edge or selvedge may be trimmed from along a length of wallpaper parallel to the body of the paper.

A further object of the invention is to provide a cutter for fabric or the like which is easily adjustable as to effective width of trim removal.

Further objects and advantages of this invention, as well as its construction, arrangement and operation, will be apparent from the following description and claims when taken in connection with the accompanying drawing, in which:

Figure 1 is a top view of the invention.

Figure 2 is a side view in section of the invention taken on line 2—2 of Figure 1.

Figure 3 is a side view in elevation of the invention.

Figure 4 is an end view in elevation of the invention; and

Figure 5 is an isometric view of the invention with a strip of fabric in cutting position, with the blade cover plate removed to show the blade and cutting action.

Figure 6 is a view in section taken along line 6—6 of Figure 1.

Referring in more particular to the drawing, in Figures 1 to 4, body 10 of the cutter has vertically bent portion 11 at substantially 90 degrees to the plane of body 10. A screw stud 12 is fixed to bent portion 11 in such a manner as to secure thereon by means of knurled nut 13 the razor blade 14 and blade cover plate 15, which is bent at right angles to have a lower portion 15' substantially parallel to the bottom plate 16.

Body 10 of the cutter is further bent along one side or otherwise formed to have a bottom plate 16. Within the substantially closed V formed by the bent body 10 is slidably positioned a second V-shaped inner plate 17 which projects partially along one edge of the body 10 and is upwardly

2

turned at gripping edge 18 in order that the inner plate 17 may be grasped and adjustably positioned within the body 10 so as to widen or make narrower the strip which passes under the blade 14.

5 A scale or other indicia 19 is printed or etched on the surface of the inner plate 17, where it protrudes from the body 10 to form a means of measuring the width of the strip to be cut from the paper or fabric. Inner plate 17 is cut back to edge 17' where it is adjacent the razor blade 14, and the uppermost side of body 10 is also cut away, leaving space 24 which is partially covered by the lower portion 15' of the blade 15. A finger or thumb may be inserted in space 24 for the purpose of advancing the paper or fabric under the razor blade. Slot 25 in the end of the body 10 permits the razor blade 14 to cross the plane of the inner plate 17 and cut any paper or fabric pulled or pushed therethrough. The body 10 is slotted for a portion of its width at 21 in order that upwardly bent and folded-over edges 22 of the inner plate 17 may be slidably engaged.

20 10 The whole of the cutter is preferentially constructed of sheet metal or other flexible material so that after the inner plate 17 is positioned by the scale 19 to the right width of strip to be cut, the body 10 may be grasped and compressed in order that the inner plate 17 be held firmly at the proper width. It is readily seen that in operation, as in Figure 5, paper 23 or other material such as fabric or sheet plastic is fed into the inner plate 17 and drawn along under the blade 14, which cuts a strip from one side of the sheet.

25 It is to be understood that various modifications and changes may be made in this invention without departing from the spirit and scope thereof, as set forth in the appended claims.

40 What is claimed is:

1. A fabric cutting tool to be held in one hand and a fabric pulled through it comprising an outer member of semi-flexible sheet material 45 folded back upon itself to form a substantially flattened V and having a portion of one side thereof bent outwardly at approximately a right angle to the plane of that side, the other side of said outer member having a slot therein substantially the length of said outwardly bent portion of the first-named side and parallel thereto, means on said outwardly bent portion constructed and arranged to removably hold a blade transverse to the plane of said outer member and 50 projecting partially through said slot, an inner

member of like material formed to a similar V and having guide channel means on one side slidably engageable with a portion of one side of said outer member for adjustably positioning said inner member relative to said outer member, the apex of the V of said inner member arranged to form a guide for one edge of a fabric while drawn through said inner member for cutting by a blade on said blade-holding means, and indicia on a side of said inner member where it projects beyond the edge of a side of said outer member while so positioned and coacting with that edge to indicate the relative position of said members and coincidentally the width of fabric between the blade and the apex of the V of said inner member.

2. A fabric cutting tool comprising an outer member of semi-flexible sheet material folded back upon itself to form a substantially flattened V and having a portion of one side thereof bent outwardly at approximately a right angle to the plane of that side, the other side of said outer member having a slot therein substantially the length of said outwardly bent portion of the first-named side and parallel thereto, means on said outwardly bent portion constructed and arranged to removably hold a blade transverse to the plane of said outer member and projecting partially through said slot, a blade cover removably secured to said blade-holding means and having a portion thereof coplanar with said first-named side of said outer member to at least partially substitute in said first-named side for said outwardly bent portion, an inner member

5
10
15

of like material formed to a similar V and having guide channel means on one side slidably engageable with another portion of said first-named side of said outer member for adjustably positioning said inner member relative to said outer member, the apex of the V of said inner member adapted to form a guide for one edge of a fabric while drawn through said inner member for cutting by a blade on said blade-holding means, indicia on the side of said inner member having guide channel means where it projects beyond the edge of said other portion of said first-named side of said outer member and coacting with that edge to indicate the relative position of said members, said indicia coincidentally indicating the distance between a line extending the line of the apex of the V of said inner member and a blade while so held on said blade-holding means, said inner and outer members constructed of such materials that a slight pressure of the sides of said outer member together will hold said inner member and outer member in desired relationship and a greater pressure will also grip a fabric within said inner member.
